REVERSIBLE PIPE PULLER

Frank L. Fraizer and Ernest H. Waltz, Troy, Ohio,
assignors to Trojan Manufacturing Company,
Troy, Ohio, a partnership

Application June 6, 1949, Serial No. 97,468

13 Claims. (Cl. 254—29)

1

This invention relates to pipe pulling apparatus, and particularly to relatively small, compact and portable devices of this kind as used by contractors, for example, in pushing and pulling pipe through conduits or directly through an earthen wall without need of excavating.

Such pipe pullers have heretofore been known as comprising a pair of movable gripping devices operating in conjunction with one another to effect a substantially continuous advance of the pipe in response to the swinging to and fro motion of the operating lever. A deficiency in the use of the prior art pullers has appeared, however, in that they are non-reversible except by the act of bodily turning the machine around so that the gripping and feeding devices work in the opposite direction. Inasmuch as many pipe hauling operations have intermixed pulling and pushing phases, the lack of simplified reversing procedure has been a distinct limitation.

The object of the invention is to simplify the construction as well as the means and mode of operation of pipe pullers as disclosed herein, whereby such devices may not only be economically manufactured, but will be more efficient and satisfactory in use, adaptable to different conditions, having relatively few parts and be unlikely to get out of repair.

A further object of this invention is to incorporate in pipe pullers of the class described a feature of reversibility whereby the gripping and feeding devices may be caused alternately to pull or to push the pipe with the same swinging motion of the actuating lever and without the necessity of changing the position of the machine.

Such object is in part attained by the interposing of an adjustable clutch mechanism between the actuating lever and the gripping and feeding devices.

A further object of the invention is to provide a neutral position of adjustment for the clutch mechanism in which the gripping and feeding devices are ineffective to act upon the pipe.

A further object is to incorporate in the clutch mechanism positions of adjustment to accommodate pipes of varying diameter for either pulling or pushing.

Still another object is to provide a machine which is generally more flexible and adaptable than those heretofore known, embodying additional features of novelty, such as a means for varying the applied power ratio.

A further object of the invention is to provide

2 a puller possessing the advantageous structural features, the inherent meritorious characteristics and the mode of operation herein mentioned.

With the above primary and other incidental objects in view as will more fully appear in the specification, the invention intended to be protected by Letters Patent consists of the features of construction, the parts and combinations thereof, and the mode of operation, as herein-after described or illustrated in the accompanying drawings, or their equivalents.

Referring to the accompanying drawing, wherein is found the preferred but obviously not necessarily the only form of embodiment of the invention,

Fig. 1 is a perspective view of a pipe pulling machine in accordance with the instant invention;

Fig. 2 is a side view of a gripping and feeding device of the puller, shown in neutral position;

Fig. 3 is a view similar to Fig. 2, showing the device with the clutch mechanism adjusted for pushing of the pipe;

Figs. 4 and 5 are partly diagrammatic views of the moving parts of the pipe puller indicating the manner in which the pair of gripping and feeding devices are operated conjointly to effect a continuous movement of the pipe; and

Fig. 6 is a view in cross section, taken along the line 6—6 of Fig. 2.

Like parts are indicated by similar characters of reference throughout the several views.

Referring to Fig. 1 of the drawings, the apparatus of the invention comprises a frame 10 made up of end members 11 and interconnecting spaced apart bars 12, which may be welded or otherwise secured into an integral structure. The end members 11 and bars 12 are L-shaped viewed in cross section, the former presenting openings 13 in their bottom portions, whereby the apparatus may be fastened to a stationary support. The upstanding portions of the end members 11 have central openings through which the pipe P is passed, bearing and alignment members 14 being fixed to end members 11 in a position of registry with the openings therein.

Pivotedly connected to the inner surface of each of the longitudinal bars 12, about mid-way along the length thereof, is one arm of a bifurcated operating lever 15, provided with a tubular shank portion 16 which may be grasped by hand for operation of the lever 15, or which may receive an extension pipe or like device when greater leverage is necessary or desirable. Each

arm of the lever 15 has a link 17 connected thereto, which links extend toward the left hand or front end of the frame and are connected at their opposite ends to levers 18. The levers 18, as viewed in Figs. 4 and 5, are pivotally connected at 19 to a respective bar 12, and each has a portion 18a extending beyond and beneath the pivot point 19. Connected to each arm 18 above the pivot point 19 is a short link 21, and connected to each portion 18a beneath pivot point 19 is a similar short link 22. Each link 21 and 22 is respectively connected to an elongated slide 23 and 24 which are mounted in superimposed relation on the bottom inturned portions of the bars 12 and extend toward the rear or right hand end of the frame.

Accordingly, and as illustrated in Figs. 4 and 5, swinging motion of the levers 18 results in a reciprocating motion of the slides 23 and 24, the strokes of the slides being in opposite relation to one another by reason of their respective connections above and below the pivot points 19. Each pair of slides, comprising an upper slide 23 and a lower slide 24, is held against vertical movement and against lateral movement in one direction by overhanging guide members 20, riveted to the bars 12.

Swinging motion of the levers 18 is initiated by manual to and fro actuation of the lever 15, which motion is transmitted to the levers 18 by the links 17. It will be noted that the links 17 are connected to the levers 18 by pins passed through a selected one of a series of openings 25 in the levers 18. A particular opening 25 is selected in accordance with the power ratio which it is desired to utilize in the operation of the levers 18, this being, of course, determined by the amount of resistance offered to movement of the pipe.

The slides 23 and 24 represent the direct means of actuating of the pipe gripping and pulling or pushing mechanism. Such mechanism is here illustrated as comprising two units 26 and 27 which are substantially identical in their construction and mode of operation. This being so, only one such unit will be here described in detail.

Referring to unit 26, for example, there is included therein a channel shaped body 28 (see Fig. 6) which includes a base portion, slidably mounted upon the inturned flanges on the bars 12, and spaced apart upstanding bracket portions 29. In the outer surface of each bracket 29 is a recess 31 constructed and arranged to receive a flat abutment member 32 secured to each slide 23. The recess 31 is wider than the abutment member 32 so as to provide a lost motion period in the operation of the body 28 by the slides 23, but, as the members 32 engage the sides of recesses 31, the body 28 is pulled or pushed along the slideway defined by bars 12. Secured within the body 28 on the base thereof is a pipe trough 33 which may, if desired, be made integral with the body. The trough 33 registers with the corresponding trough in unit 27 and with the bearing members 14 on the frame and receives and guides the pipe P as indicated in Fig. 6.

The upper ends of the brackets 29 support therebetween a pivot pin 34. Pivotally mounted upon the pin 34, in overlying relation to the trough 33, is a gripping jaw 35. The jaw 35 has a relatively narrow elongated shape. Its underside is arcuate shaped in its longitudinal dimension and substantially concave in its lateral or transverse dimension. Further, such underside is serrated to provide grip-

ping teeth 36. The upper surface of the jaw 35 has an angular formation, sloping upwardly and outwardly from its mid-portion, through which portion the pivot pin 34 is passed.

Also pivotally mounted upon the pin 34 in the plane adjacent to the jaw 35 is a segmental shaped clutch plate 37. As shown in Fig. 6, the plate 37 has an integral projecting rib 38 on its inner surface terminating in an arm 39 pivotally mounted on the pin 34 on the opposite side of the jaw 35. A curved rod 41 has its ends anchored in the upper surface of the jaw 35 adjacent the ends thereof and passes through the projecting rib 38 of the clutch plate 37. Coil springs 42 and 43 surround the rod 41 and are interposed between the jaw 35 and respective sides of the rib 38. The construction and arrangement is such as to center the clutch plate 37 with respect to the jaw 35, and to provide a yielding connection between the jaw and plate.

The peripheral surface of the clutch plate 37 is formed with a first or left hand series of notches 44, and with a second or right hand series of notches 45, and with a central or intermediate notch 46. Cooperative with the notches 44, 45 and 46 is a clutch dog 47 pivotally mounted upon the pin 34 in the plane adjacent to the plate 37. The clutch dog 47 is formed on its upper end with a flange 48 overlying the peripheral edge of plate 37. The flange 48 carries and has passed therethrough a wing-nut bolt 49. By relative rocking motion between the plate 37 and dog 47, the bolt 49 may be caused to register with a selected one of the notches 44, 45 and 46, and the bolt may then be turned down to enter the selected notch to engage the clutch dog with the clutch plate.

The clutch dog 47 has a stud 51 set therein which is received in a slot or recess in the top of the adjacent abutment member 32. Accordingly, motion of the abutment member 32 in response to axial movement of the slide 23 serves to rock the clutch dog 47 and, with it, the plate 37 and jaw 35 about pivot pin 34. The extent of rocking motion permitted the assembly, comprising dog 47, plate 37, and jaw 35, is limited to the extent of motion permitted abutment member 32 relatively to the body 28, and occurs within the lost motion period previously described.

In the operation of the unit, it will be understood that the peripheral notches in the plate 37 and the selective engagement therewith of the clutch dog 47 is productive of reversing means, whereby either the to or fro stroke of the slides 23 may be utilized to effect gripping engagement of the jaw 35 with the pipe. Thus, if the clutch dog 47 is engaged in one of the notches 44, such preliminary positioning of the clutch plate will result in the right hand end of the jaw 35 approaching more closely to the trough 33 and the pipe mounted therein. Accordingly, when the slide 23 moves in a right hand direction, as viewed in Figs. 2 and 3, the initial limited motion of abutment member 32 relative to body 28 is effective, through clutch dog 47 and plate 37, to move the jaw 35 the additional distance required to place it into gripping engagement with the pipe. Similarly, if the clutch plate and jaw 35 are preliminarily positioned so as to lock the clutch dog 47 in one of the notches 45, the left hand end of the jaw 35 is caused to approach the trough 33 and pipe P. In this instance, therefore, leftward motion of the slide 23 is effective to cause the

Jaw to grip the pipe; whereas, rightward motion of the slide effects release of the pipe.

When the parts are positioned as shown in Fig. 2, with the clutch dog locked in the notch 46, the mechanism is in a neutral position. That is, motion of the slide 23 in either the rightward or leftward direction is effective to engage the jaw with the pipe. It will be further understood that the several notches 44 and 45 of the left hand and right hand series are selected for co-operation with the clutch dog 47 in accordance with the diameter of the pipe.

Considering a typical operation of the unit, and assuming that the clutch dog 47 and the plate 37 are adjusted as shown in Fig. 3, motion of the operating lever 15 in a leftward or counterclockwise direction serves to rock the levers 18 in a similar direction. Accordingly, the slides 23 are pulled leftwardly. The start of such motion finds the abutment members 32 against the right hand side of the recesses 31 in the brackets 29, and the body 28 shifted to a rightward position. Further, jaw 35 is in gripping engagement with the pipe. As the slides 23 begin their leftward or rearward travel, the abutment members 32 move, for a brief interval, relatively to the brackets 29 until they engage the opposite side edges of the recesses 31. In this interval of lost motion, the one abutment member is effective, by reason of its connection with clutch dog 47, to rock the clutch plate 37 and jaw 35 in a counterclockwise direction, moving the jaw out of gripping engagement with the pipe. Now, as the abutment members engage the side edges of the recesses 31, the body 28 begins to move with the slides and the clutch and jaw elements are carried therewith. The body and its associated parts thereby is returned or restored to a starting position.

When the lever 15 is swung in the opposite direction, or in a clockwise direction of movement, as viewed in Fig. 1, the levers 18 are similarly moved and the slides 23 are pushed forwardly, or to the right. During the initial phase of this motion, the abutment members 32 move within the recesses 31 relatively to the body 28 and are effective to rock the clutch dog 47, plate 37, and jaw 35 in a clockwise direction to place the jaw in gripping engagement with the pipe. As rightward or forward motion of the slides 23 continues, abutment members 32 engage or pick up the brackets 29 and shift the body and its associated parts to exert a pulling or pushing influence upon the pipe, which, being gripped between the jaw 35 and trough 33, is carried with the body. The pressure exerted through the clutch dog 47 and clutch plate 37 upon the jaw 35 is a yielding pressure by reason of the springs 42 and 43.

The second gripping and pulling unit 27 operates in the same manner as the first, and, further, is arranged to act in conjunction therewith to utilize both the to and fro rocking motions of the lever 15 to advance the pipe. Thus the unit 27 is operated by the slides 24, which, since they move oppositely in timed relation to the movements of the slides 23, cause unit 27 to grip and pull the pipe during the period that unit 26 is releasing the pipe and being retracted to starting position. Similarly, as unit 26 grips and pulls the pipe, unit 27 is being released and retracted by the slides 24. These conjoint operations of the units 26 and 27 upon the pipe are indicated in the partly diagrammatic views, Figs. 4 and 5. From the above description it will be apparent that there is thus provided a device of the char-

acter described possessing the particular features of advantage before enumerated as desirable, but which obviously is susceptible of modification in its form, proportions, detail construction and arrangement of parts without departing from the principle involved or sacrificing any of its advantages.

While in order to comply with the statute the invention has been described in language more or less specific as to structural features, it is to be understood that the invention is not limited to the specific features shown, but that the means and construction herein disclosed comprise but one of several modes of putting the invention into effect.

Having thus described our invention, we claim:

1. A reversible pipe puller, including a movable body having a trough to receive a length of pipe and a pair of upstanding brackets on the opposite sides of said trough, a pivot pin supported between said brackets, an arcuate gripping jaw pivotally mounted on said pin in overlying relation to said trough, said jaw being movable alternatively to engage the ends thereof with a pipe in said trough, a clutch plate mounted on said pin and having a series of notches in its periphery, oppositely disposed yielding means between said clutch plate and the opposite ends of said jaw tending to connect said plate and jaw for motion as a unit but permitting relative motion therebetween, a clutch dog selectively engageable in the peripheral notches in said plate, and reciprocal means acting in one direction of motion initially to move said clutch dog to engage said jaw with the pipe and subsequently to shift said body to advance the pipe and acting in the opposite direction of motion initially to move said clutch dog to release said jaw from the pipe and subsequently to return said body independently of the pipe, the advance of the pipe occurring during a direction of motion of said reciprocal means predetermined by the position of adjustment of said clutch dog upon said clutch plate.

2. A reversible pipe puller, including a movable body presenting a trough to receive a length of pipe and a pair of upstanding brackets on the opposite sides of said trough, a pivot pin supported between said brackets, an arcuate gripping jaw pivotally mounted upon said pin in overlying relation to said trough, a segmental shaped clutch plate mounted on said pin and having left hand and right hand series of peripheral notches, a connection between said plate and said jaw, a clutch dog pivotally mounted on said pin and settable selectively into the notches on said plate according to whether the pipe is to be pulled or pushed and in accordance with the diameter of the pipe, reciprocal means operatively connected to said dog, and a connection between said reciprocal means and said body providing for a lost motion period during which period said clutch dog is operated to engage said jaw with the pipe in one direction of motion and to disengage said jaw from the pipe in the opposite direction of movement.

3. A reversible pipe puller, including a movable body presenting a trough to receive a length of pipe and a pair of upstanding brackets on the opposite sides of said trough, a pivot pin supported between said brackets, an arcuate gripping jaw pivotally mounted upon said pin in overlying relation to said trough, a segmental shaped clutch plate mounted on said pin and having left hand and right hand series of peripheral notches,

a yielding connection between said plate and said jaw, a clutch dog pivotally mounted on said pin and adjustable relative to said plate for selective engagement within the peripheral notches in the plate, said adjustment being predetermined as to said series by the desired direction of motion of the pipe and as to the notches in a series by the diameter of the pipe, and a reciprocatory actuator connected to said clutch dog and operable upon said body, there being a lost motion period in the operation of said body by said actuator during which period said clutch dog is effective to engage and disengage said jaw with respect to the pipe in respective directions of movement of said actuator.

4. A reversible pipe puller, including a movable body presenting a trough to receive a length of pipe and a pair of upstanding brackets on the opposite sides of said trough, a pivot pin supported between said brackets, an arcuate gripping jaw pivotally mounted upon said pin in overlying relation to said trough, a segmental shaped clutch plate mounted on said pin and having left hand and right hand series of peripheral notches, a yielding connection between said plate and said jaw, a clutch dog pivotally mounted on said pin and adjustable relative to said plate for selective engagement within the peripheral notches in the plate, said adjustment being predetermined as to said series by the desired direction of motion of the pipe and as to the notches in a series by the diameter of the pipe, an abutment member pivotally connected to said clutch dog, a recess in one of said body brackets receiving said abutment member, said recess being wider than said abutment member, and a reciprocatory slide secured to said abutment member and operable therethrough to reciprocate said body, the lost motion of said abutment member in said recess being utilized to engage and disengage said gripping jaw with respect to the pipe.

5. A reversible pipe puller according to claim 4, characterized by a second movable body and gripper jaw mechanism in series with and the same as the mechanism described, and a swinging lever arranged to push and pull the reciprocatory slides of said first and second mechanism in inverse relation to one another.

6. A reversible pipe puller, including a movable body presenting a trough to receive a length of pipe, a reciprocatory actuating slide for said body, a connection between said slide and said body providing for a lost motion period in the operation of said body by said slide, a gripping jaw supported by said body in overlying relation to said trough, clutch means between said slide and said jaw for moving said jaw into gripping engagement with a pipe in said trough during the lost motion period in the movement of said slide in one direction and for moving said jaw out of gripping engagement during the lost motion period of said slide in the opposite direction, and a reversing connection in said clutch means for utilizing alternatively the directions of movement of said slide for gripping and releasing the pipe.

7. A reversible pipe puller, including a movable body presenting a trough to receive a length of pipe and a pair of upstanding brackets alongside said trough, a recess in the outer surface of each said brackets, a reciprocatory slide arranged alongside each said brackets, an abutment member secured to each of said slides and received in a respective recess of an associated bracket to accomplish to and fro shifting motion of said movable body in response to reciprocation of said

slides, said abutment members being of lesser width than said recesses whereby to define a lost motion period at the start of each stroke of the slides, a pivot pin supported between the brackets, an arcuate shaped gripping jaw pivotally mounted on said pin, a clutch plate mounted on said pivot pin and presenting left and right hand series of notches in its periphery, a compression spring interposed between said clutch plate and each end of said gripping jaw centering said plate relatively to said jaw and establishing a resilient connection therebetween, and a clutch dog mounted on said pivot pin and pivotally connected to one of said abutment members, said clutch dog being cooperatively engageable with a selected one of the series of notches in said clutch plate and operable in said lost motion periods to move said gripping jaw into and out of gripping engagement with a pipe in said trough, the gripping and releasing motions of said jaw bearing a relation to the strokes of said slide predetermined by the adjustment of said clutch dog relatively to said clutch plate.

8. A reversible pipe puller according to claim 7, characterized by a central notch in said clutch plate representing a neutral position in which said clutch dog is ineffective to move said jaw into gripping engagement with the pipe in either direction of motion of said slide.

9. A pipe puller including a relatively stationary frame, first and second movable bodies slidably mounted on said frame in series relationship, said bodies presenting aligned pipe troughs, a slide movably mounted on each side of said bodies for shifting said first body in a to and fro direction, another slide on each side of said bodies for similarly shifting said second body, gripping means associated with each said bodies and operable to grip and release the pipe length in timed relation to and in response to actuation of said slides, an actuating lever pivoted to the frame for the pair of slides on each side of said bodies, links interconnecting each of said levers to individual slides of each pair, one of said links being connected to a lever above its pivot point and the other link being connected to the lever beneath the pivot point, an actuator for effecting a simultaneous rocking motion of said levers about their pivots, and means for applying a greater and lesser power ratio to said levers from said actuator.

10. In a pipe puller having a pair of oppositely reciprocating pipe grippers, means for reciprocating said grippers and means for automatically engaging said grippers with a pipe in timed sequence with the travel motion of the grippers and in predetermined directions of said travel motion, including a resiliently mounted jaw assembly pivotally supported on each of said grippers, a retaining latch engageable with said jaw assembly, means for engaging said latch and jaw assembly in different positions of relative adjustment, the relative adjustment of said latch and jaw assembly determining the direction of travel in which said jaw engages the pipe, means for oscillating the jaws and engaged latches about the pivot point prior to initiation of reciprocatory movement of the grippers, and means for actuating said grippers through simultaneous reciprocatory movements in opposite directions.

11. In a pipe handling apparatus, a pair of reciprocating pipe gripping members, actuating means therefor, a lost motion clutch mechanism interconnecting the actuating means and the grippers, a jaw assembly carried by each gripper

and operatively connected with the clutch mechanism for engaging the jaw assembly and gripper with a pipe to be handled, and means for adjusting said jaw assembly relative to the clutch mechanism to determine the direction of reciprocatory movement of the grippers during which the grippers and associated jaw assembly is engaged with the pipe.

12. In a pipe handling apparatus, a pair of reciprocatory pipe grippers, actuating means therefor whereby the grippers are simultaneously actuated in opposite directions of reciprocatory movement, oscillatory means carried by each gripper for resiliently engaging a pipe to be handled, and a reversible clutch mechanism interconnecting the actuating means and grippers, adjustment of which determines the direction of gripper travel during which the pipe is resiliently engaged by the gripper.

13. In a pipe handling apparatus, a pair of reciprocatory pipe gripping members, each said member including a jaw adjustable into and out of gripping engagement with a pipe common

to said members, an actuating lever movable to and fro, linkage interconnecting said actuating lever and said members and operable to reciprocate said members in an opposed relation to one another, a lost motion connection in said linkage, clutch means operable from said linkage to adjust said jaws during the lost motion period, and individual controls in said clutch means settable from a neutral position wherein said jaws may not engage the pipe to alternative positions wherein the jaws engage the pipe during either the to or fro motion of the actuating lever.
